UNITED STATES PATENT OFFICE.

CHARLES A. CYPHERS, OF BUFFALO, NEW YORK, ASSIGNOR, BY MESNE ASSIGNMENTS, TO MODEL INCUBATOR COMPANY, OF BUFFALO, NEW YORK, A CORPORATION OF NEW YORK.

THERMOSTAT.

No. 873,511.

Specification of Letters Patent.

Patented Dec. 10, 1907.

Application filed December 7, 1905. Serial No. 290,791.

To all whom it may concern:

Be it known that I, CHARLES A. CYPHERS, a citizen of the United States, residing at Buffalo, in the county of Erie and State of New York, have invented certain new and useful Improvements in Thermostats; and I do hereby declare the following to be a full, clear, and exact description of the same, reference being had to the accompanying drawings, forming a part of this specification, and to the figures and letters of reference marked thereon.

This invention relates to thermostats and more especially thermostats designed for controlling or regulating the temperature of artificially heated compartments such as the hatching chambers of incubators or the brooding chambers of brooders.

The objects of the invention are to provide a thermostat of compact construction with a wide range of thermostatic action, sensitive to slight variations in temperature, responding quickly to any change in temperature and finally rigid to any pressure applied in a direction tending to destroy or vary the thermostatic action.

The invention contemplates a thermostat embodying oppositely bowed members and an intermediate straight member, the bowed and straight members having different coefficients of expansion, all of said members being formed with longitudinally extending corrugations registering or nesting with each other to permit the members to lie close together.

The invention further contemplates a thermostat composed of a series of duplicate sections, the corrugations of the adjacent members of the different sections registering or nesting together centrally while the corrugations of the members in each section register or nest together remote from the center.

The invention further contemplates a member for thermostats having a substantially flat central part and end parts with longitudinal corrugations throughout the member intermediate said flat portions.

The invention consists in certain novel details of construction and combinations and arrangements of parts all as will be now de-

scribed and pointed out particularly in the appended claims.

In the accompanying drawings—Figure 1 is a perspective view of a thermostat embodying the present improvements. Fig. 2 is a side elevation of the same. Fig. 3 is a section on the line 3—3 of Fig. 2. Fig. 4 is a section on the line 4—4 of Fig. 2. Fig. 5 is a section on the line 5—5 of Fig. 2, Figs. 3, 4 and 5 being drawn to the same scale. 60

Similar letters of reference in the several figures indicate like parts.

In the drawings, the thermostat is shown without the damper or devices to be controlled by it although the operating connections are shown in the form of a connecting rod A extending centrally through the members of the thermostat and adjustably connected with or having an adjustable bearing a' engaging the lower member, while an adjustable tubular supporting device B is connected with the upper member. The action of the thermostat causes a relative movement of the parts A and B which may be utilized as usual to operate any suitable heat 75 controlling devices such as a damper, a valve or a flame regulator as heretofore.

In the preferred form the thermostat is made up of three sections D, E and F, the number of sections, however, being purely 80 arbitrary, although the invention, as will presently appear, has, in part, to do with a construction whereby a number of sections may be assembled in compact form so as to occupy but a small space and at the same time 85 secure a wide range of movement and a high degree of sensitiveness with a maximum rigidity of the parts in all positions.

Each of the sections is preferably made up of three members, two of which lettered H 90 are bowed members and the third, lettered I, substantially straight and the bowed members have a higher coefficient of expansion than the central member.

To reduce the thickness of the sections 95 both individually and collectively and also to make a rigid structure the members are corrugated longitudinally throughout their width and the corrugations register and nest together where the members approach each 100

other; thus the central members are corrugated as at i throughout their length save for short ends where the members are secured together and the bowed members are corrugated as at h intermediate the center and each end. The central parts h' and the end parts h^2 are preferably substantially flat in cross section and in these parts the necessary slight flexibility or bending takes place during the thermostatic action of the device. Intermediate the flat portions, the members are rigid by reason of their corrugated form, thus the material may be very thin so as to be quickly affected by changes of temperature of the surrounding air.

It will be noted that the bowed sections are duplicates in that both may be struck up in the same dies and in assembling them, it is only necessary to bow one in one direction and the other in the opposite direction, the bending taking place in the narrow flattened parts at the ends and centers.

The width of the strips from which the members are formed is preferably uniform from end to end but the metal is drawn in in the corrugated parts thereby having the flat parts in the complete formation somewhat wider. This construction insures a uniform distribution of the metal and results in a device having a uniform and regular action.

The sections are secured together centrally as by rivets K and it will be noted that at the points where members of adjacent sections approach each other the corrugations register, thus the complete thermostat may be made up of a large number of sections without becoming springy or elastic and will occupy but a minimum vertical space.

While rivets are shown as the fastening means for securing the members together in each section and for securing the sections themselves together, it is obvious that other well known fastening means may be employed.

The advantage of the cumulative action of a series of sections is well understood and common to thermostats of this type, but the present thermostat is believed to be the first wherein the parts are made rigid against spring action by corrugating the bodies of the members themselves and making the corrugations register wherever the members approach each other.

As the most convenient and efficient materials having a widely different coefficient of expansion, zinc and steel are preferably employed.

Having thus described my invention, what I claim as new and desire to secure by Letters Patent, is:—

1. In a thermostat, the combination of a substantially straight member and a bowed

member having different coefficients of expansion, secured together rigidly at the ends and having registering corrugations formed longitudinally thereof intermediate the ends; said bowed member being adapted to bend intermediate its ends when affected by changes in temperature; substantially as described.

2. In a thermostat, the combination with a straight member corrugated longitudinally throughout its width, of a bowed member secured rigidly to the straight member at the ends and having longitudinal corrugations registering with the corrugations of the straight member; said members having different coefficients of expansion and the bowed member being adapted to bend intermediate its ends when affected by changes in temperature; substantially as described.

3. In a thermostat the combination with an intermediate straight member corrugated longitudinally, of bowed members having a different coefficient of expansion therefrom located on opposite sides thereof and secured rigidly thereto at the ends, said bowed members having longitudinal corrugations registering with the corrugations of the straight members and being adapted to bend intermediate their ends when affected by changes in temperature; substantially as described.

4. In a thermostat, the combination of a plurality of sections, each composed of longitudinally corrugated substantially straight and bowed members secured together, said straight members having a coefficient of expansion different from that of said bowed members, the corrugations of the members and sections registering with each other in proximity to the points of union and the bowed members being adapted to bend intermediate their ends when affected by changes in temperature.

5. In a thermostat, the combination of a plurality of sections, each composed of straight and bowed members having different coefficients of expansion corrugated longitudinally throughout their width, the corrugations registering in proximity both to the points of connection between the members of the sections and to the points of connection between the sections and the bowed members being adapted to bend intermediate their ends when affected by changes in temperature; substantially as described.

6. In a thermostat, the combination of a plurality of sections secured together centrally, each section being composed of a straight and two bowed members secured to opposite sides of the straight member adapted to bend in action and having a different coefficient of expansion therefrom, said members being corrugated longitudinally and the

corrugations registering in proximity to the points of union between the members; substantially as described.

7. A thermostat member formed up from an elongated strip of sheet metal of substantially uniform width, said member having a central substantially flat portion capable of bending transversely of the member and end portions longitudinally corrugated through-

out their width and merging into the central 10 flat portion whereby the end portions are stiffened and the bending in action confined to the flat portion of the member; substantially as described.
